UNITED STATES PATENT OFFICE.

SAMUEL BRONSTIEN, OF ST. PAUL, MINNESOTA.

NONSTRETCHABLE MATTRESS.

Application filed June 3, 1922. Serial No. 565,580.

To all whom it may concern:

Be it known that SAMUEL BRONSTIEN, a citizen of the United States, residing at St. Paul, in the county of Ramsey and State 5 of Minnesota, has invented certain new and useful Improvements in Nonstretchable Mattresses, of which the following is a specification, reference being had to the accompanying drawings.

10 This invention relates to mattresses and it is an object of the invention to provide a novel and improved mattress constructed in a manner whereby the same is non-stretchable.

15 Another object of the invention is to provide a novel and improved mattress involving a method of shrinking the edges down to a given size.

20 The invention consists in the details of construction and in the combination and arrangement of the several parts of my improved mattress whereby certain important advantages are attained and the device rendered simpler, less expensive and otherwise 25 more convenient and advantageous for use, as will be hereinafter more fully set forth.

The novel features of my invention will hereinafter be definitely claimed.

25 In order that my invention may be the better understood, I will now proceed to describe the same with reference to the accompanying drawings, wherein:

Figure 1 is a view in top plan with a portion broken away of a mattress constructed 30 in accordance with my invention.

Figure 2 is a fragmentary view in perspective illustrating a means herein embodied for tightening the holding strips associated with the box strips; and

35 Figure 3 is a diagrammatic view illustrating the manner of cutting either the top or bottom of the mattress to obtain the desired shrinkage to assure the maintenance of the completed mattress against stretching.

40 As disclosed in the accompanying drawings, 1 denotes either the top or bottom of a mattress which has associated in a conventional manner with the marginal portion thereof, the box strip 2. Secured to 45 the strip 2 at the sides and ends of the mattress are the flaps F, the flaps at the 50 sides of the mattress being in opposed relation as is also the case in connection with the flaps carried by the ends of the mattress.

55 Each of the flaps F comprises a sheet of material of requisite dimensions and folded

upon itself to provide the overlying laminations 3. The flap F is connected preferably by the stitching 4 to the transverse center of the boxing strip 2 and the outer longitudinal marginal portion of said flap F has disposed therethrough a plurality of eyelets or gromets 4 providing openings through which is adapted to be disposed the lacing cord 5.

60 Substantially bridging the space between a pair of opposed flaps F is a strip 6 of a width substantially the same as the width of the flaps F. The extremities of the strip 6 are provided with the eyelets or gromets 7 through which the lacing cord 5 is disposed. The lacing cords 5 serve to provide 65 effective means to pull the strip 6 taut.

70 The advantage of the co-acting strips 6 and flaps F is to assure the proper building 75 of the mattress. In cutting the top or bottom to a size of four feet eleven inches in width and six feet eleven inches in length in sewing up the mattress approximately one inch is taken up in both width and 80 length, bringing the net size to four feet ten inches by six feet ten inches. The upholsterer takes in through the center the slack which will bring the size of the mattress 85 down to a basis of four feet six inches by six feet three inches. The flaps each have one and one-half inches free and as the longitudinal strips 6 and transverse strips 6 are six feet one inch and four feet four inches, respectively, the excess on the flaps 90 F is one and one-half inches on each end of the strips 6, making a total length of six feet four inches and four feet seven inches, respectively. The cords 5 serve to take up 95 the excess and resulting in a frame that is exactly four feet six inches in width and six feet three inches in length. The mattress on this basis cannot possibly stretch. The efficiency of the cords 5 is further 100 facilitated in view of the fact that the eyelets or gromets 4 and 7 are positioned one-fourth inch inwardly of the adjacent edges of a flap F or strip 6.

105 To further facilitate the maintenance of the mattress against stretching or distortion I find it of advantage to initially cut the end portions of the top or bottom of the mattress as is diagrammatically illustrated in Figure 3. The top or bottom 1, after being initially cut in the desired dimensions, 110 has each corner cut therefrom on the slanted line of cut a, said line of cut a being from

a point substantially one and one-half inches inwardly of the longitudinal edge of the top or bottom and to a point substantially ten inches inwardly of the adjacent 5 end of said top or bottom.

Each end of the top or bottom at a point substantially two and one-half inches inwardly thereof at its sides is cut on the lines *b* to the transverse center of the top or bottom 10 to *1* at a point *c* substantially one and one-half inches inwardly of the adjacent end edge of said top or bottom *1*.

By cutting the end portion of the fabric of the top or bottom *1* on this basis one and 15 one-half inches of slack is taken up at each end which gives a total of three inches slack taken up in the width. At the same time two and one-half inches in length is taken up at each end portion or a total of five 20 inches. This computation occurs only at the extreme edges of the top or bottom of the mattress but there is a gradual take up from the longitudinal edges to the transverse center of the top or bottom. The 25 shrinkage at the transverse center of the top or bottom is 1 inch or one-half inch at each end so therefore the upholsterer need only take up six inches in upholstering.

After the ends of the top or bottom *1* have 30 been cut on the lines *a* and *b* as hereinbefore referred to, it is only necessary to round off the corners as at *d* to make a round cornered mattress.

From the foregoing description it is 35 thought to be obvious that a mattress constructed in accordance with my invention is particularly well adapted for use by reason of the convenience and facility with which it may be assembled, and it will also be obvious 40 that my invention is susceptible of some change and modification without departing from the principles and spirit thereof and for this reason I do not wish to be understood as limiting myself to the precise 45 arrangement and formation of the several parts herein shown in carrying out my invention in practice except as hereinafter claimed.

I claim:

50 1. A tufted mattress comprising, in combination, a top, a bottom, a box strip associated with the top and bottom, said top and bottom being initially of a length in excess of the length of the finished mattress, said top and bottom each having its opposite end 55 portions cut on lines converging from the sides thereof toward the transverse center, said converging ends at the sides of the mattress being spaced apart a distance equal to the finished length of the mattress, the tufting of the mattress drawing in the intermediate parts of the end portions of said top and bottom, and strips connecting the end 60 portions of the box strip, the connections between said strips and the box strip being spaced apart a distance substantially equal to the length of the finished mattress, the end portions of the box strip, the connections between said strips and the box strip being 65

spaced apart a distance substantially equal to the length of the finished mattress.

2. A tufted mattress comprising, in combination, a top, a bottom, a box strip associated with the top and bottom, said top and bottom being initially of a length in excess of the length of the finished mattress, said top and bottom each having its opposite end portions cut on lines converging from the sides thereof toward the transverse center, said converging ends at the sides of the mattress being spaced apart a distance equal to the finished length of the mattress, the tufting of the mattress drawing in the intermediate parts of the end portions of said top and bottom, strips connecting the end portions of the box strip, the connections between said strips and the box strip being spaced apart a distance substantially equal to the length of the finished mattress, the top and bottom each being initially of a width greater than the finished width of the mattress, the extremities of the sides of the top and bottom being each cut on a slanting line from a point inwardly of the ends to a point at the ends of said top and bottom inwardly of the sides thereof, the inner extremities of said cut portions at each end of the top and bottom being spaced apart a distance substantially equal to the width of the finished mattress, and strips connecting the side portions of the box strip, the connections of each of said strips with the side portions of the box strip being spaced apart a distance substantially equal to the width of the finished mattress.

3. A tufted mattress comprising, in combination, a top, a bottom, a box strip associated with the top and bottom, said top and bottom being initially of a length in excess of the length of the finished mattress, said top and bottom each having its opposite end portions cut on lines converging from the sides thereof toward the transverse center, said converging ends at the sides of the mattress being spaced apart a distance equal to the finished length of the mattress, the tufting of the mattress drawing in the intermediate parts of the end portions of said top and bottom, and strips connecting the end portions of the box strip, the connections between said strips and the box strip being spaced apart a distance substantially equal to the length of the finished mattress, each of the connecting strips comprising separable sections.

4. A tufted mattress comprising, in combination, a top, a bottom, a box strip associated with the top and bottom, said top and bottom being initially of a length in excess of the length of the finished mattress, said top and bottom each having its opposite end portions cut on lines converging from the sides thereof toward the transverse center, said converging ends at the sides of the 12

mattress being spaced apart a distance equal to the finished length of the mattress, the tufting of the mattress drawing in the intermediate parts of the end portions of said top and bottom, strips connecting the end portions of the box strip, the connections between said strips and the box strip being spaced apart a distance substantially equal to the length of the finished mattress, said top and bottom each being initially of a width greater than the finished width of the mattress, the extremities of the sides of the top and bottom being each cut on a slanting line from a point inwardly of the ends 15 to a point at the ends of said top and bot-

tom inwardly of the sides thereof, the inner extremities of said cut portions at each end of the top and bottom being spaced apart a distance substantially equal to the length 20 of the finished mattress, and strips connecting the side portions of the box strip, the connections of each of said strips with the side portions of the box strip being spaced apart a distance substantially equal to the 25 width of the finished mattress, each of the connecting strips comprising separable sections.

In testimony whereof I hereunto affix my signature.

SAMUEL BRONSTIEN.
